UNITED STATES PATENT OFFICE.

HENRY C. GORDON, OF MUNCIE, INDIANA, ASSIGNOR TO HIMSELF, CHARLES S. DAVIS,
AND J. CARL O'HARRA, TRUSTEES, ALL OF MUNCIE, INDIANA.

DESIGN FOR AN ELECTRIC HEATER.

60,337.

Specification for Design.

Patented Feb. 7, 1922.

Application filed April 7, 1921. Serial No. 459,483. Term of patent 14 years.

To all whom it may concern:

Be it known that I, HENRY C. GORDON, a citizen of the Dominion of Canada, residing at Muncie, in the county of Delaware and State of Indiana, have invented a new, original, and ornamental Design for Electric Heaters, of which the following is a specification, reference being had to the accompanying drawing, forming part hereof.

In such drawing, Fig. 1 is a perspective view, taken from the top, of an electric

heater, showing my new design; Fig. 2 is a bottom plan of such heater; and Fig. 3 is a side elevation of such heater.

I claim as my invention:

The ornamental design for an electric heater, as shown.

In witness whereof, I have hereunto set my hand at Indianapolis, Indiana, this 22nd day of March, A. D. one thousand nine hundred and twenty-one.

HENRY C. GORDON.
